(57) **CLAIM**

The ornamental design for a chair having water receptacles for hands and feet, as shown and described.

DESCRIPTION

FIG. 1 is a front view of a chair having water receptacles for hands and feet.

FIG. 2 is a rear view of the chair.

FIG. 3 is a right side view of the chair with a water-circulating device in phantom.

FIG. 4 is a left side view of the chair with the water-circulating device in phantom.

FIG. 5 is a top plan view of the chair.

FIG. 6 is a bottom plan view of the chair.

FIG. 7 is a sectional view of a portion of the water receptacle for feet taken along line 7—7 of FIG. 5.

FIG. 8 is a sectional view of a portion of the water receptacles for hands taken along line 8—8 of FIG. 5.

FIG. 9 is a referential drawing showing the chair in use with the water-circulating device; and,

FIG. 9 and the phantom representation made in FIGS. 3 and 4 are shown merely for the purpose of illustrating the environment in which this invention is used. The structure shown in dotted lines is not part of the design sought to be patented.

The broken lines showing a machine, hose attachment, and human form is for illustrative purposes only and forms no part of the claimed design.
